ATTORNEYS

UNITED STATES PATENT OFFICE.

WILLIAM V. GIST, OF ST. JOSEPH, MISSOURI, ASSIGNOR OF ONE-HALF TO DE WITT C. McCALL, JR., OF ST. JOSEPH, MISSOURI.

HOSE HOUSING.

Application filed March 28, 1924. Serial No. 702,648.

To all whom it may concern:

Be it known that I, WILLIAM V. GIST, a citizen of the United States, and resident of St. Joseph, in the county of Buchanan and 5 State of Missouri, have invented certain new and useful Improvements in Hose Housings, of which the following is a specification.

My invention is an improvement in hose 10 housings and it consists in the combinations, constructions and arrangements herein described and claimed.

An object of the invention is to provide a device of simplified construction which 15 affords facilities for supporting a garden hose or like elongated flexible article in coiled formation and in sheltered position.

Another object of the invention is to provide a device of the character described 20 which is adapted to permit of the support therein of a length of hose without there being any necessity of detaching the hose at one end from a source of water supply or like connection.

25 A further object of the invention is to provide a housing of the character described in which the length of hose may be placed in coiled formation quickly and easily and from which the hose may be partially or 30 completely removed as desired.

A still further object of the invention is to provide a housing of the character described which affords facilities for supporting a length of hose so that water will drain 35 therefrom and the hose will dry quickly and so that twisting or entangling of the convolutions of the hose is obviated.

Other objects and advantages will be apparent from the following description, considered in conjunction with the accompanying 40 drawings, in which—

Figure 1 is a perspective view showing the housing embodying the invention with a length of hose supported therein.

45 Figure 2 is a vertical section through the outer casing of the device with an inner casing and the hose thereon being shown partly in vertical section and partly in side elevation, and

50 Figure 3 is a perspective view of a supporting base which is comprised in the device.

A device embodying the invention comprises a substantially frusto-conical outer casing or shell 1, a frusto-conical inner cas-

ing or frame 2, a base indicated generally at 3 and attaching brackets 4 carried by the base and secured to the inner casing 2 and the outer casing 1 for securing said casings upon the base in spaced concentric relation 60 in respect to each other.

The outer casing or shell 1 is of greater length than the inner casing 2 and is provided at its upper and smaller end with a relatively short substantially cylindrical portion 1^a. The base 3 comprises a pair of flat bars 5 crossed intermediate their length and having the crossed portions thereof secured together by a suitable fastening device, such as the rivet 6. Each 70 bar 5 is bent adjacent to its ends to extend in a general downward direction, as at 7, and then outward, as at 8, so that the portions 7—8 of the bars 5 constitute legs for supporting the major portions of the bars 5 in 75 spaced parallel relation to any suitable horizontal supporting surface, as 9.

The end portions of the bars 5 of the base carry the attaching members 4, each of which comprises an intermediate portion secured upon an end portion of one of the bars 5 and a pair of parallel end portions upstanding from the intermediate portion and being slightly inclined inward or toward the axis of the base 3, the respective 80 upstanding end portions of each of the attaching members 4 being spaced radially on the base. The outer casing or shell 1 receives the crossed intermediate portions of the base 3 and rests upon the downwardly 85 turned portions 7 of the base supporting members, the outer casing or shell 1 also being in contact adjacent to its lower end with the outer upturned end portions of the attaching brackets 4 and being secured to 90 such outer upturned end portions by fastening devices, such as the rivets 10. The inner casing 2 rests upon the body of the base with the lower end portion thereof in contact with and secured by rivets 11 or like 95 fastening devices to the inner upturned end portions of the attaching members 4.

From the foregoing description of the various parts of the device, the operation thereof may be readily understood. The 105 outer casing 1 serves as a protective shell while the inner casing or frame 2 and the annular portion of the base 3 between the casings 1 and 2 at the lower ends of the latter together form a support for a length 110

of hose 12 or like flexible elongated article, the hose being disposed within the space between the sheltering casing 1 and supporting casing 2 in coiled formation, the coils 5 decreasing in diameter toward the upper end of the device and the lowermost coil resting upon the base 3. Since the base 3 is formed of crossed bars, it is obvious that the hose receiving space within the body is 10 completely open at the upper end of the device and is partially open at the lower end of the device so that the hose may be disposed therein without there being any necessity of detaching the hose from a 15 source of water supply or other pipe connection. The nozzle end of the hose of course will be disposed uppermost and the nozzle may extend from the cylindrical upper end portion of the outer casing in 20 position to be conveniently grasped so that any desired portion of the hose stored within the device may be withdrawn for use. The body of the base is in effect a spider and the spaces between the arms thereof 25 permit the draining of water from the coils of hose and from the inner or supporting casing 2.

The outer casing 1 is provided with the cylindrical or flared upper end portion 1^a 30 so that the hose may be manipulated with relatively great ease when it is desired to place the hose within the device or to withdraw any desired portion of the hose from position on the supporting casing 2.

35 Obviously, my invention is susceptible of embodiment in forms other than that illustrated in the accompanying drawings and I therefore consider as my own all such modi-

fications and adaptations of the form of the device herein described as fairly fall 40 within the scope of the appended claims.

I claim:—

1. A device of the character described comprising a base, a tapering supporting member secured upon said base, a protective casing secured upon said base in encircling spaced relation to said supporting member, said casing being open at its upper end, said base comprising a pair of bars crossed intermediate their ends and being provided with 45 depending supporting portions.

2. A device of the character described comprising a substantially frusto-conical outer casing, a substantially conical inner casing adapted to be disposed within the outer casing in spaced concentric relation to the latter, and a base on which said casings are supported, said base comprising a pair of bars crossed intermediate their 50 length and having downwardly turned supporting end portions.

3. A device of the character described comprising a base, a substantially frusto-conical outer casing adapted to be supported on said base with the smaller end of the 55 casing uppermost, a substantially frusto-conical supporting casing adapted to be supported on said base within the outer casing in spaced concentric relation to the latter, attaching members carried by said base for 60 securing said casings to the base and for holding said casings in spaced parallel relation, said outer casing extending above the level of the inner casing and being flared outward at its upper end.

WILLIAM V. GIST.
